UNITED STATES PATENT OFFICE.

EZRA E. CLARK, OF NEWTONVILLE, MASSACHUSETTS, ASSIGNOR TO FIRE PROTECTION SECURITIES COMPANY, OF BOSTON, MASSACHUSETTS, A CORPORATION OF MASSACHUSETTS.

DRY-PIPE VALVE.

1,291,411.

Specification of Letters Patent. Patented Jan. 14, 1919.

Application filed August 27, 1917. Serial No. 188,284.

To all whom it may concern:

Be it known that I, EZRA E. CLARK, a citizen of the United States, residing at Newtonville, county of Middlesex, State of Massachusetts, have invented an Improvement in Dry-Pipe Valves, of which the following description, in connection with the accompanying drawing, is a specification, like characters on the drawing representing like parts.

This invention relates to novel improvements in dry pipe valves.

Valves of this general type are employed in automatic sprinkler systems and include a water valve and an air valve and are so constructed that the pressure of the air confined in the sprinkler system will hold closed the water valve against the pressure of the water in the supply pipe. These dry pipe valves are, further, so constructed that a lesser air pressure will hold the water valve closed against the greater water pressure. This is usually accomplished by a system of levers or by the use of differential valves or by a combination of both. This invention preferably employs the differential type in which the air valve is of greater area than the opposed water valve.

The object of this invention is to provide a dry pipe valve that will be compact, efficient, inexpensive and easy to maintain.

A more specific object is to provide a dry pipe valve in which the valves are so mounted that the space required by them, in their unseated positions and in swinging from seated to unseated positions, is restricted to a minimum.

Other objects of the invention will more fully appear from the following description and accompanying drawings and will be pointed out in the annexed claims.

In the accompanying drawings there has been illustrated a selected embodiment of this invention but it is to be understood that it is illustrative but not restrictive and that various changes may be made within the scope of the claims.

In the drawings:

Figure 1 is a vertical median section through the casing;

Fig. 2 is a section on the line 2—2 of Fig. 1, the valve being omitted;

Fig. 3 is a plan view of the valve, the outside of the casing being omitted,

In this preferred embodiment of the invention, the casing 1 substantially incloses the whole dry pipe valve and is provided at its upper end with an outlet opening 2 which is adapted to be connected to the automatic sprinkler system normally containing air under pressure. The lower end of the casing is provided with an opening 3 to be connected with the usual riser or pipe of the water supply always under pressure. The openings 2 and 3 are preferably in alignment so that a substantially straight waterway is provided through the casing for the water permitted to be forced therethrough upon the unseating of the air valve and water valve by the release of a sprinkler head and consequent reduction of air pressure in the sprinkler system. A covered hand-hole 4 is also provided in the casing through which the valve structure may be inserted or removed from the casing, while a smaller opening or hand-hole 4^A is made to permit examination or resetting of the valve. The plugged opening 5 permits of machining the respective seats of air valve and water valve in a machine shop boring mill.

In this preferred construction, the inlet 6 is substantially cylindrical and extends well within the casing in alignment with the outlet opening 2. The upper end of the inlet 6 is provided with a valve seat 7 upon which is seated an annular portion of the water valve 8 which normally closes the water inlet 6. The inlet is so formed that the valve 8 occupies a position inclined to the vertical. This inclined valve seat may be viewed as formed by passing a cutting element through the cylindrical inlet diagonally to its vertical axis. This would produce an elliptical valve seat, and the valve could be thus constructed. But for machine shop reasons, the cylindrical inlet 6 has its upper terminal portion slightly curved from the vertical, as shown in Fig. 1 to permit the use of a circular valve seat. This circular valve seat accommodates a circular valve both of which are less expensively and more easily produced than the elliptical forms, while the increase in friction loss caused by the slight curvature of the waterway is so slight as to be practically negligible. The air valve 9 is provided with a similarly inclined valve seat 10. This valve seat is placed on an annular shoulder 11 preferably integral with

the casing casting. These two valve seats are desirably concentric and their differential function is attained by making the air valve of greater area, as shown, than the 5 water valve. This inclination of the seated valve structure not only causes the natural force of gravity to aid and accelerate the latter portion of the movement of the valve structure to unseated position but also the 10 direction of inclination shortens the path traveled by the structure to unseated substantially vertical position.

This air valve 9 substantially separates the casing interior into upper and lower 15 chambers. The upper chamber, comprising all that above the air valve, is subjected normally to the air pressure in the sprinkler system through the outlet opening 2, and therefore the whole upper surface of the air 20 valve is subjected to this air pressure. The lower chamber comprises all that between the valves and is normally open to the atmosphere.

The air valve and the water valve are 25 preferably concentric and are desirably joined together in one valve structure. These joint valves substantially function as a unit in their operative movements. As here shown, the water valve 8 is secured to 30 and carried by the larger air valve 9. A threaded stud bolt 13 with nut and washer secures the water valve to the air valve, in sufficiently loose adjustment to permit the water valve readily seating itself. The upper portion of the central annular flange 15 is interiorly threaded to receive the plug 16. This construction effectually prevents leakage of air at this union of the two valves. A plurality of reinforcing webs 17 radiate 35 from this annular flange.

The perimeter of the air valve 9 is provided with a circumferentially projecting flap or ring washer 18 of a suitable flexible material, such as rubber. This flap or 40 washer is held to the valve by means of the clamping ring 19 and yieldingly engages the valve seat 10 thus assuring an air-tight valve seating.

In addition to efficiency and durability, 45 compactness of construction and the resultant economy of space in dry pipe valve installations are highly desirable. In this embodiment, there is provided a construction which permits of a material reduction of 50 the space required by the dry pipe valve due to the novel mounting of the water and air valves so that the space, occupied by the valves in their unseated positions and required by them in moving from seated to 55 unseated position, is reduced to a modicum. This result is achieved by providing these joint valves with a mechanism such as a link motion which guides the valve structure in its movement from its seated position to an

unseated position where it stands close to 65 and substantially parallel to the water way.

In this selected embodiment of this invention, there is shown for this purpose a link motion comprising two systems of link members pivotally mounting the differential 70 valve structure in the casing. A pair of opposed links 20 are shown as constituting one of the link systems and each has one end secured to one side of the valve and the other end secured to the casing, thus straddling 75 the water way. The links 20 (see Fig. 3) are alike and the upper end of each engages with suitable pin bearings 25 through both of which extends the pin 22. The valve casting between the links has a central cored 80 out portion 24 to reduce pin friction while the two end portions or bearings 25 are fitted with bushings for the pin 22 which is retained in the bearing at each end by means of the retaining plugs 26. Each link 20 85 is movable on a preferably diametrically opposite side of the inlet 6 to the other. The lower end of each link is similarly pivotally mounted. As shown in Figs. 1 and 2, this lower pin 28 is preferably inserted in two 90 parts, one from each side of casing. End bearings 29 for these two pins 28 are afforded by the casing 1.

The second link system is shown as a single link 30. This system can, if desired, 95 be arranged in two parts similar to links 20, and placed outside of valve structure, but to secure compactness, it is arranged, as shown, as one link wholly within the neutral or atmospheric chamber. This link is relatively 100 broad and is pivotally secured to the air valve by means of its integral transverse bearing sleeve 31 through which is passed the pin 32. The pin 32 is borne by the two preferably integrally cast bearing bosses 33. 105 The other end of this link has a similar sleeve 49 pivotally borne by a pin 50 mounted in end bearings 51 formed on the casing.

These link systems are so proportioned and positioned, preferably as illustrated, 110 that the valve structure moves in a short path to a substantially upright position beyond the waterway and adjacent to the outer wall of the inlet 6.

The air valve is preferably integrally cast 115 to provide chambers to inclose the upper portions of the link system. The dotted line position of the open, unseated valves in Fig. 1 indicates the restricted movement which the valves have when released. A projection 34 is provided on the lower end portion of the air valve and is adapted to bear upon the shoulder 35 of the casing and thus prevent the weight of the unseated valves from finding support on the yielding flap 18 of the air valve. This flap 18, as shown in dotted lines in Fig. 1, does not touch the casing 1. 120 125

The lower chamber 36, as already stated, is normally open to the atmosphere. For this purpose an outlet 37 to the atmosphere is provided in this lower chamber and therein is positioned a sleeve 38 on which is provided a valve seat 39 to receive the valve 40 carried by a stem 41 having a pin and slot connection 42 with one arm 43 of a bell-crank lever fulcrumed at 44 on the outside 5 of the inlet 6. This lever structure functions normally to hold the outlet valve 40 unseated while the air valve is seated and, upon unseating of the air valve, automatically permits the dropping of the valve 40 to closed position and also prevents the reseating of the air valve. The upper arm 45 of the lever has its end normally in a recess 46 formed in the under side of the air valve 9 so that, when the air valve is in normal 10 seated position, the other arm 43 of this lever functions to hold the outlet valve away from its seat and thus to maintain this lower chamber at the pressure of the atmosphere. Further, this lever engagement with the air 15 valve is such that upon unseating of the air valve and release of the arm 45, the latter will assume a position more nearly normal to the air valve and will effectually prevent accidental re-seating of the air valve with a 20 column of water in the upper chamber and air system pipes which would subsequently prevent the proper functioning of the dry pipe valve. This construction therefore overcomes the disadvantageous "columning" 25 feature. Provision is also preferably made to overcome the undesirable chattering of the dry pipe valves. This is effected by means of the provision of a plurality of stepped notches 47 on the upper end of the 30 lever arm 45.

Upon a relatively slight upward movement of the air valve 9, the lowest notch 47 will engage the upper edge of the recess 46 and hold the air valve in a slightly raised 35 but still seated position; further chattering of the valve will cause the next high notch to engage the recess edge, while any extraordinary chattering will cause the lever arm 45 to be released from the recess 46 whereby 40 the outlet 37 will be closed and the air valve held open. Air and water may then enter 45 the lower chamber, the differential function of the valves is destroyed and the dry valve will be thrown to open position.

The circular seat 10 of the air valve and the circular seat 7 of the water valve are desirably concentric and in transverse inclined alinement; but, as a matter of practical construction it is deemed preferable to allow 50 for a little relative positioning of the two joined valves. Therefore, the under side of the air valve 9 is desirably provided with an annular concaved surface 48 to engage an annular convex surface upwardly presented

by the water valve. This construction functions in the nature of a ball-joint and automatically permits adjustment of the relative positions of the valves in a plurality of directions. The remainder of the surface of each valve is out of contact with the other and the space therebetween is maintained at atmospheric pressure due to its communication with the lower chamber 36. 65

There is thus provided an efficient and durable dry pipe valve which has the advantages of a straight waterway unobstructed by the unseated valves and yet is compact and may occupy a relatively small space. 70

Having thus described my invention, what I claim as new and desire to secure by Letters Patent is:

1. A dry pipe valve comprising a casing, a water valve and an air valve connected to form a single valve structure, the water valve being of less area than the air valve, 85 valve seats therefor, link members pivotally mounting the differential valve structure in the casing and acting upon unseating of the valves to guide the valve structure in a short restricted path to a position outside of the 90 waterway.

2. A dry pipe valve comprising a casing, a water valve and an air valve connected to form a single valve structure, the water valve being of less area than the air valve, 95 valve seats therefor, link members pivotally mounting the differential valve structure in the casing and acting upon unseating of the valves to guide the valve structure in a short restricted path to a vertical position close 100 to one side of the waterway.

3. A dry pipe valve comprising a casing, a water valve and an air valve connected to form a single valve structure, the water valve being of less area than the air valve, 105 valve seats therefor, link members pivotally mounting the differential valve structure in the casing and acting upon unseating of the valves, to guide the valve structure in a short restricted path to one side of and substantially parallel with the waterway. 110

4. A dry pipe valve comprising a casing, a water valve and an air valve connected to form a single valve structure, a link system comprising a pair of opposed links straddling the waterway, one end of each being pivoted to the valve structure and the other end of each to the casing, a second link system comprising a single link pivoted to the valve structure at one end and to the casing 120 at the other end, the said second link system being materially shorter than the first, whereby upon unseating of the valves, the valve structure is caused to describe a short restricted path to one side of and substantially parallel with the waterway. 125

5. A dry pipe valve comprising a casing, having inlet and outlet openings, valves and

- valve seats normally closing each opening, the valves being connected to form a single valve structure, links pivotally securing the valve structure to the casing, a cylindrical inlet extending within the casing, and having its valve seat inclined, whereby, upon unseating, the valve structure is guided by the links in a short path to one side of the casing, the inlet being curved to present a circular inclined valve seat.
6. A dry pipe valve comprising a casing having an air valve, a valve seat therefor, a water inlet extending within the casing, a valve seat thereon, an inlet-closing valve of less area than the air valve, the differential

valves being connected to form a single valve structure, a link system comprising links movable on opposite sides of the inlet, each link having one end secured to the valve structure and the other pivotally mounted on the inlet, a second link system secured to the valve structure and pivotally mounted on the casing and acting with the said links to cause the valve structure to turn from seated to unseated position in a short restricted path close to one side of the inlet.

In testimony whereof, I have signed my name to this specification.

EZRA E. CLARK.
